UNITED STATES PATENT OFFICE.

ERNEST L. TEICH, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

LOCK.

1,195,292.

Specification of Letters Patent. Patented Aug. 22, 1916.

Application filed March 24, 1916. Serial No. 86,392.

To all whom it may concern:

Be it known that I, ERNEST L. TEICH, a citizen of the United States, residing at New Britain, county of Hartford, State of Connecticut, have invented a certain new and useful Improvement in Locks, of which the following is a full, clear, and exact description.

My invention relates to improvements in locks, and has for its object to provide the external knob of the lock with a secret releasing member so that one unfamiliar with that class of locks would not naturally release the mechanism, so as to be unable to unlatch the door upon grasping the knob in the manner in which knobs are ordinarily grasped.

My invention is applicable to locks and latches of various types and can be embodied to advantage in locks having various means for dogging the latch and also to control means for retracting the latch which cannot be dogged.

I have embodied my invention in a lock 25 of the type shown in patent to Byron Phelps, No. 834,994, granted November 6, 1906, and it possesses some especial advantages when embodied in such a lock.

The following is a description of an embodiment of my invention, reference being had to the accompanying drawings, in which:

Figure 1 shows the plan view of a lock; Fig. 2 shows a part of the frame and escutcheon of the lock and the knob, partly in section on the line corresponding to the axis of the knobs Fig. 1 with my secret holding and releasing means in engaging position; Fig. 3 is a similar view with my holding and releasing means in retracted position; Fig. 4 shows an end elevation of the knob removed from the spindle and with the secret catch member removed; Fig. 5 shows an end elevation of a projection from 45 the lock frame, showing notches with which the catch member engages; Fig. 6 shows in end and side elevation the engaging catch member of my secret holding and releasing means. Fig. 7 is a partial horizontal section 50 with the side plates omitted showing the dogging means. Fig. 8 is a partial vertical section for the same purpose. Fig. 9 is a side and end elevation of the dog controlling means.

Referring more particularly to the draw-

ings, which for convenient use or illustration show what is known as a Unit lock, 1 is the lock frame; 2 are the escutcheon plates; 3 is a pivoted latch bolt; 4 is the ordinary slide or shoe connected to the latch bolt 3 and engaged by roll-backs 5—5', the latch bolt being normally held in extended position by the spring 6 in the ordinary manner. The roll-back 5' can be actuated by the knob 7 or by the key 8 under all circumstances. When the roll-back 5 is in the position shown, it can be actuated by the knob 9. The roll-back 5, however, can be moved to the left so as to engage or enter a recess in the lock frame, this being accomplished by the turning of the ring 10. When the roll-back is in this position the latch bolt 3 is dogged against operation by the knob 9, although the latch bolt 3 can be retracted through the roll-back 5' either by the knob 7 or key 8. The key controlled means acts to turn the inside knob. These features are clearly described in the Phelps Patent No. 834,994, above referred to. Reference is made to that patent for further description of the elements just referred to and their operation. It is to be noted that the outside knob 9 can be dogged or undogged against the operation of the latch 3.

Sneak thieves, and other persons, often 85 try outside knobs to see whether they are dogged or not, and it has been found desirable to apply to knobs which may be dogged or undogged a secret catch so that improper persons trying the knob will gain the impression that the outside knob is dogged although that may not really be the case. In order to accomplish this result I surround the spindle of the knob 9 with a sleeve 11 having one or more projections 12, which engage recesses 13 in the knob, whatever may be the position of the sleeve 11. I also provide in the knob chambers 14 for springs 15 which normally press the sleeve 11 away from the knob and toward the frame of the lock. Upon an extension from the frame of the lock I provide notches 16—16 with which the projections 12 upon the sleeve 11 engage when the sleeve is forced toward the lock frame and the knob 9 is in a position 100 to permit the latch 3 to be extended.

The mechanism controlled by the ring 10 for dogging the outer knob is shown in detail in Figs. 7, 8 and 9. The ring 10 is provided with a cam surface 17, which engages 110

a pin 18 moving in a longitudinal slot in the knob shank and carried by the longitudinal rod 19 against the right hand end of which bears a spring 20. To this rod 19 the roll-back 5 is secured so that it is free to rotate but whenever the rod 19 is moved longitudinally in either direction the roll-back 5 travels with it. The roll-back 5 surrounds the rod 19 and is not affected or controlled thereby. Both of these roll-backs lie in notches 21 formed on the inner opposing ends of the shanks of the knobs 7 and 9. The frame of the lock is provided with a notch 22, into and out of which the roll-back 5 can be moved by the rod 19. When the roll-back 5 is in the notch 22, the knob 9 is thereby locked against turning. When it is removed from said notch 22, the knob 9 can be turned so as to retract the latch 3. 20 The rod 19 is adjusted by the cam ring 10. When this ring is turned to the position shown in Fig. 8, so that the low part of the cam is in line with the pin 18, the spring 20 pushes the rod 19 to the left so as to move the roll-back 5 into the notch 22 and thus dog the knob 9. When the ring 10 is turned about 90°, the cam surface 17 acts to move the pin 18 so as to shift the rod 19 to the right and thus remove and hold the roll-back 5 out of the slot 21 so as to undog the knob 9.

Fig. 2 shows the latch member 11 with the projections 12 engaging the notches 16. With the parts in this position, when the knob 9 is grasped in the ordinary manner, it is held against turning without regard to whether it is dogged or not. If, however, the knob is grasped so that the fingers extend to the rear thereof, the sleeve 11 can be easily retracted to the position shown in Fig. 3, at which time the knob 9 if undogged can be turned so as to withdraw the latch 3. By this means described a very simple and inconspicuous secret detent is provided, 45 which will prevent anyone turning the outside knob of a lock unless they withdraw the secret detent, a thing which they are not likely to do unless they are aware of its presence. This secret detent provides means giving the impression that the outside knob is dogged even when that is not the case.

As will be evident, my secret detent may be applied to knobs that cannot be dogged and thus give the impression that a door is 55 really locked when there is no lock upon it, but only a simple latch. The best results are accomplished, however, when the lock upon which my device is used is upon a door which ordinarily would or might be dogged. 60 As will be evident to those skilled in the art, my invention permits of various modifications without departing from the spirit thereof, or the scope of the appended claims.

What I claim is:

65 1. In combination, a latch, a latch frame

therefor, an outside knob and roll-back for retracting said latch, a detent accessible from the same side as said knob for holding said knob from rotation relative to said frame so that it cannot actuate said roll-back, said 70 detent when in holding position engaging both said knob and a stationary portion connected to said latch frame, and means normally tending to force said detent member into engagement with said frame, said de- 75 tent being manually operable from the outside of the door, and an inside knob rotatable independently of said outside knob for retracting said latch.

2. In combination, a latch, a latch frame 80 therefor, a knob and roll-back for retracting said latch, a detent carried by said knob for holding said knob from rotation relative to said frame, said detent when in holding position engaging both said knob and a stationary portion connected to said latch frame, and means normally tending to force said detent into engagement with said frame, said detent forming a sleeve surrounding the 85 spindle of said knob.

3. In combination, a latch, a latch frame 90 therefor, a knob and roll-back for retracting said latch, a detent carried by said knob for holding said knob from rotation relative to said frame, said detent when in holding position engaging both said knob and a stationary portion connected to said latch frame, and means normally tending to force said detent into engagement with said frame, said detent forming a sleeve surrounding the spindle of said knob, said knob 95 having a recess partially receiving said sleeve.

4. In combination, a latch, a latch frame 100 therefor, an outside knob and roll-back for 105 retracting said latch, a detent carried by said knob for holding said knob from rotation relative to said frame, said detent when in holding position engaging both said knob and a stationary portion connected to 110 said latch frame, means normally tending to force said detent into engagement with said frame, and additional means for dogging said knob so that it cannot retract said latch, said additional means being inaccessible 115 from the outside when the latch is attached to a door.

5. In combination, a latch, a latch frame 120 therefor, an outside knob and roll-back for retracting said latch, a detent carried by 125 said knob for holding said knob from rotation relative to said frame, said detent when in holding position engaging both said knob and a stationary portion connected to said latch frame, means for normally tending to force said detent into engagement with said frame, additional means for dogging said knob so that it cannot retract said latch, said additional means being inaccessible from the outside when said latch is at- 130

- tached to a door, and key-controlled means for retracting said latch bolt from the outside independently of the position of said detent.
- 5 6. In combination, a latch, a latch frame therefor, an outside knob and roll-back for retracting said latch, a detent carried by said knob for holding said knob from rotation relative to said frame, said detent when 10 in holding position engaging both said knob and a stationary portion connected to said latch frame, means for normally tending to force said detent into engagement with said frame, additional means for dogging said 15 knob so that it cannot retract said latch, said additional means being inaccessible from the outside when said latch is attached to a door, key-controlled means for retracting said latch bolt from the outside independently 20 of the position of said detent, and an inside means for retracting said latch bolt independently of the position of said detent.
7. In combination, a latch, a latch frame therefor, an outside knob and roll-back for 25 retracting said latch, a detent carried by said knob and accessible from the outside of the door for holding said knob from rotation relative to said frame, said detent when in holding position engaging both said knob and 30 a stationary portion connected to said latch frame, means for normally tending to force said detent into engagement with said stationary portion, additional means for dogging said knob so that it cannot retract said latch, 35 said additional means being inaccessible from the outside when said latch is attached to a key controlled means for retracting said latch bolt from the outside independently 40 of the position of said detent, and an inside knob for retracting said latch bolt independently of the position of said detent, the key controlled means accessible from the outside of the door acting to turn said inside knob.

ERNEST L. TEICH.
